PLASTIC RUNNER

Dana W. Mox, Glenview, Ill., assignor to Tenex Corporation, a corporation of Illinois

Filed Sept. 25, 1967, Ser. No. 8,722

Term of patent 14 years

Int. Cl. D5—03

U.S. Cl. D92—4

FIG. 1 is a plan view of a plastic runner showing my new design, the design is shown broken away to indicate indeterminate length;

FIG. 2 is a fragmentary enlarged view thereof;

FIG. 3 is a fragmentary enlarged cross sectional view of FIG. 2 taken on the line 3—3; and

FIG. 4 is a fragmentary enlarged cross sectional view of FIG. 2 taken on the line 4—4.

I claim:

The ornamental design for a plastic runner, substantially as shown.
